SUPERREGENERATIVE WAVE-SIGNAL
TRANSLATING SYSTEMJasper J. Okrent, Great Neck, N. Y., assignor to
Hazeltine Research, Inc., Chicago, Ill., a corporation of Illinois

Application September 24, 1946, Serial No. 698,997

1 Claim. (Cl. 250—20)

1

This invention is directed to superregenerative wave-signal translating systems, such as superregenerative receivers, of the type which have a separate quench-voltage supply.

As is well understood in the art, a superregenerative receiver essentially comprises a regenerative oscillatory circuit the conductance of which is controlled to have positive and negative values during alternate operating intervals. The conductance variations characteristic of superregenerative operation may be obtained by virtue of self-blocking effects within the regenerative circuit or, for arrangements of the type to which this invention particularly relates, may result from the influence of a periodic quench voltage supplied from an oscillator or other source external to the regenerative circuit. Where a separate quenching source is utilized, it is customary to adjust the degree of regeneration, the operating bias of the regenerator, and the amplitude of the quench voltage for optimum reception. Receivers adjusted in this manner have proved to be satisfactory for most installations but they are subject to one operating limitation which may be objectionable in certain cases. Specifically, the amplitude of the quench voltage tends to vary with such factors as the voltage regulation, tube characteristics, etc. in the quench oscillator. Where the quench voltage does experience a change in amplitude, the operating conditions required for optimum reception no longer prevail and the response of the receiver is adversely affected.

It is an object of the present invention, therefore, to provide a new and improved superregenerative wave-signal translating system which at least partially avoids the aforementioned limitation of prior arrangements.

It is another object of the invention to provide a new and improved superregenerative wave-signal translating system of the type that features a separate quench-voltage source and is characterized by an operating bias which varies with amplitude variations in the quenching voltage.

It is a specific object of the invention to provide a new and improved superregenerative receiver having an external quench supply and a biasing arrangement which compensates for amplitude variations of the quenching voltage.

A superregenerative wave-signal translating system in accordance with the invention is of the separately quenched type and comprises a regenerative oscillatory circuit and an oscillation generator, including a self-biasing means, for applying a periodic quench voltage to the regener-

2

ative circuit to control the conductance thereof to have positive and negative values during alternate operating intervals, as required to provide superregeneration. The system also has means for deriving from the self-biasing means of the generator and for applying to the regenerative circuit a unidirectional bias potential having a magnitude determined by and variable with the amplitude of the quench voltage.

10 For a better understanding of the present invention, together with other and further objects thereof, reference is had to the following description taken in connection with the accompanying drawing, and its scope will be pointed out in the appended claim.

In the drawing, Fig. 1 is a schematic representation of a superregenerative receiver embodying the present invention; and Fig. 2 represents a modified receiver arrangement also embodying the invention.

20 Referring now more particularly to Fig. 1, the wave-signal translating system there represented is a superregenerative receiver that is of conventional design and construction except for 25 the potential-supply arrangement which embraces the invention and renders the receiver performance substantially independent of amplitude variations of the quench voltage. As illustrated, the receiver comprises a regenerative oscillatory circuit including a triode-vacuum tube 10 having anode, cathode and control electrodes. The operating frequency of the regenerative circuit is determined by the parallel combination of an inductor 11 and a condenser 12, the latter being represented as a variable element to facilitate adjusting the operating frequency to a desired value. The resonant circuit 11, 12 is coupled to the anode and control electrodes of tube 10 by way of condensers 13 and 14, respectively.

30 35 40 A tap of inductor 11 is grounded as is the cathode of tube 10 to provide regeneration in conventional manner. The anode of the tube is connected to a source of space current +B by way of a filter and an anode resistor 15. The filter includes serially connected signal-frequency chokes 16 and 17 as well as intermediate shunt-connected condensers 18 and 19.

45 50 55 Superregenerative operation is achieved by controlling the conductance of the described regenerative oscillatory circuit in accordance with a periodic quench voltage applied thereto from a quench-voltage supply means in the form of an oscillation generator. This generator includes a second triode-vacuum tube 25 arranged in an oscillatory circuit of the Hartley type. The fre-

quency-determining circuit of the quench oscillator comprises an inductor 26 in parallel with an adjustable condenser 27 and is coupled to the control electrode of tube 25 through a grid condenser 28 and a grid-leak resistor 29. The anode of tube 25 is effectively connected with the frequency-determining circuit by means of a condenser 30, while the cathode thereof is directly coupled to a tap on inductor 26. A source of space current $+B$ is coupled to the anode of the tube through a resistor 31 and the quench-signal output is derived from the cathode circuit for application to tube 10 of the regenerative circuit through a condenser 32 and a radio-frequency choke 33. A by-pass condenser 34 is associated with the output connection from the quench oscillator to isolate radio-frequency signals therefrom. The quench signal supplied by oscillator 25 may have a sinusoidal or other suitable wave form but has a frequency which is low with reference to the operating frequency of the regenerative circuit including tube 10.

A unidirectional bias potential for regenerator 10 is obtained from means, included in the oscillation generator, for rectifying the quench voltage. While this means may take the form of a discrete and separate rectifier circuit, it is expedient to utilize grid condenser 28 and resistor 29 which constitute a peak-rectifying self-biasing system in the quench oscillator. A connection extending from a tap on resistor 29 and including a resistor 35 provides means for applying a bias potential derived in a circuit of the quench-frequency oscillator along with the quench voltage to the control electrode circuit of regenerator tube 10.

A condenser 40 couples a detector system to the regenerative circuit for detecting the signal output thereof to obtain the desired modulation components of a received signal. The detector system has a diode 41 and its load circuit includes a signal-frequency choke 42 and a resistor 43 bypassed by a condenser 44. The output signal of the receiver may be derived from the load circuit of the detector and supplied to any suitable utilizing circuit (not shown) as indicated by the arrow 45. Received signals may be applied to the receiver from an antenna-ground system 46, including an inductor 47 inductively coupled with resonant circuit 11, 12.

In considering the operation of the receiver, it will be understood that the degree of regeneration of the regenerative circuit and the bias applied thereto from resistor 29 are adjusted with reference to the normal value of the quench voltage to effect optimum wave-signal reception. The quench voltage controls the conductance of the regenerative circuit, causing it to have positive and negative values in alternate operating intervals in conventional superregenerative fashion. The oscillations generated in the circuit of tube 10 during negative conductance intervals are applied to detector 41. These oscillations carry the modulation of the received signal which is obtained in the detector system and delivered to the utilizing circuit.

Grid current flows in the circuit of tube 25 during the peak-amplitude periods of the generated quench oscillations. This flow of grid current is equivalent to peak rectification of the quench voltage and develops across resistor 29 a substantially unidirectional bias potential having a magnitude which is determined by and variable with the amplitude of the quench voltage. This potential accomplishes two functions. It serves as

a self-bias for the oscillator and, through the tap of resistor 29, it is used as an operating bias for the regenerator tube 10. Inasmuch as the bias thus applied to regenerator tube 10 is obtained directly from and varies in the same sense as the amplitude of the quench voltage, it compensates for any amplitude changes in the quench voltage, thereby maintaining the superregenerative action substantially independent of variations in the quench amplitude as required to maintain optimum reception.

In the modification of Fig. 2 the regenerative circuit includes a section S₁ of a duo-triode tube 50. The frequency-determining circuit in this case is provided by an inductor 51 and a condenser 52, shown in broken-line construction since it may be comprised in whole or in part of the distributed capacitance of inductor 51 and associated stray capacitance effects. One terminal of this circuit is grounded and the high-potential terminal thereof is connected to the control electrode of tube section S₁ through a condenser 53. The cathode of this section is grounded and the anode circuit includes an inductor 54 coupled with inductor 51 as a feed-back connection.

The quench oscillator in the Fig. 2 embodiment comprises the alternate section S₂ of tube 50. Its frequency-determining circuit is provided by an inductor 55 and a condenser 56. Condenser 56 is also connected with the anode circuit of tube section S₁ and applies the generated quench voltage to the anode-cathode circuit of the regenerator. Resonant circuit 55, 56 is also coupled to the control electrode of tube section S₂ through a condenser 57 and a grid-leak path including serially connected resistors 58 and 59. The latter is bypassed by a condenser 60 and has a tap from which a bias potential is derived and applied by way of a signal-frequency choke 61 to the control electrode of regenerator tube S₁. A source of space current $+B$ is connected to the anode element of tube section S₂ through an inductor 62 which also affords the required feedback for the quench oscillator.

A detector system, including a diode 41, is coupled to the regenerator in a manner similar to that described in connection with Fig. 1 and furnishes the output signal of the receiver to a utilizing circuit as represented by the arrow 45. An antenna-ground system 65, including an inductor 66 coupled to inductor 51, is provided for applying received signals to the regenerative circuit.

The arrangement of Fig. 2 is essentially the same as that of Fig. 1 and their operation is generally similar. It will be noted, however, that in Fig. 2 the only potential applied to the anode-cathode circuit of the regenerator tube S₁ is the quench voltage, there being no direct-current potential included in this path. The advantage in this is that the bias applied to the regenerator substantially compensates the entire effects of variations of the B supply in the receiving system. This is to be distinguished from the Fig. 1 arrangement wherein B-supply variations modify the anode potential of tube 10 in addition to changing the anode potential of the quench oscillator.

In each of the illustrated arrangements the automatically adjustable bias of the regenerator tube follows amplitude variations of the quench voltage. This tends to maintain the positive and negative values of conductance alternately exhibited by the regenerator substantially independent of changes in the quench amplitude.

For this reason the performance of the receiver is improved over those arrangements wherein there is no compensating relationship between the quench amplitude and the regenerator bias.

While there have been described what are at present considered to be the preferred embodiments of this invention, it will be obvious to those skilled in the art that various changes and modifications may be made therein without departing from the invention, and it is, therefore, aimed in the appended claim to cover all such changes and modifications as fall within the true spirit and scope of the invention.

What is claimed is:

A superregenerative wave-signal translating system of the separately quenched type comprising: a regenerative oscillatory circuit; an oscillation generator, including a self-biasing means, for applying a periodic quench voltage to said circuit to control the conductance thereof to have positive and negative values during alternate operating intervals to provide superregeneration; and means for deriving from said

self-biasing means of said generator and for applying to said circuit a unidirectional bias potential having a magnitude determined by and variable with the amplitude of said quench voltage.
